UNITED STATES PATENT OFFICE.

LEWIS D. NELSON, OF UNION CITY, MICHIGAN, ASSIGNOR OF ONE-HALF TO ROBERT M. NEALE, OF UNION CITY, MICHIGAN.

AIR-HEATING ATTACHMENT FOR INTERNAL-COMBUSTION ENGINES.

1,313,639.

Specification of Letters Patent.

Patented Aug. 19, 1919.

Application filed September 19, 1917. Serial No. 192,110.

To all whom it may concern:

Be it known that I, LEWIS D. NELSON, a citizen of the United States, residing at Union City, Michigan, have invented certain new and useful Improvements in Air-Heating Attachments for Internal-Combustion Engines, of which the following is a specification.

This invention relates to improvements in 10 internal combustion engines.

The main objects of this invention are:

First, to provide in an internal combustion engine an improved structure in which the exhaust and inlet manifolds are housed 15 so that the inlet manifold is heated, the housing constituting an air heater for the carburetor.

Second, to provide a structure having these advantages which is adapted to be applied to automobile engines of well known 20 type, such as the Ford, without materially changing the same and without the necessity for drilling or tapping for securing the added parts.

25 Further objects, and objects relating to details and economies of construction and operation will definitely appear from the detailed description to follow.

I accomplish the objects of my invention 30 by the devices and means described in the following specification. The invention is clearly defined and pointed out in the claims.

A structure constituting a preferred embodiment of my invention is illustrated in 35 the accompanying drawing forming a part of this specification, in which:

Figure I is a detail side elevation of the structure embodying the features of my invention, various parts being shown conventionally.

Fig. II is a detail vertical transverse section on a line corresponding to line 2-2 of Fig. I.

45 Fig. III is a vertical longitudinal section on a line corresponding to line 3-3 of Figs. II and IV.

Fig. IV is a horizontal longitudinal section on a line corresponding to line 4-4 of 50 Fig. III.

Fig. V is a rear view of the housing with the rear section of the intake manifold pipe extension removed.

Fig. VI is an inside view of the removable 55 section of the intake pipe extension.

Fig. VII is a detail section through one of the housing valves on a line corresponding to line 7-7 of Fig. II.

In the drawing similar reference characters refer to similar parts throughout the 60 several views, and the sectional views are taken looking in the direction of the little arrows at the ends of the section lines.

Referring to the drawing, 1 represents the body of an engine such as that employed in 65 a Ford automobile, the same being shown mainly in conventional form. 2 indicates the exhaust manifold and 3 the intake manifold thereof. The carburetor 4 is also shown conventionally.

70 The manifolds are secured by the clamping yokes 5 and the bolts 6. The bolts shown at 7 are the usual cylinder head bolts. The bolts 6 are bolts substituted for the clamping bolts commonly employed for securing the manifolds, the bolts 6 being extended beyond the yoke engaging nuts 8 through holes 9 in the housing 10 and receive the nuts 11, thereby clamping the housing to the side of the engine.

80 The housing 10 comprises the front wall 12, top wall 13, bottom 14 and ends 15, the engine constituting the rear wall of the housing when it is applied thereto. The top wall of the housing is provided with a rib 75 or shoulder 16 which engages the head of the engine, as shown in Fig. II with the top wall lapping upon the head. The top wall is provided with holes indicated at 17 adapted to receive the head bolts 7. The bottom 85 wall of the housing has angular shoulders 18 adapted to engage the shoulders 19 of the engine body. By this arrangement of parts the housing is effectively secured by means of the head and the manifold clamping bolts 90 so that it is unnecessary to tap the engine body or provide other securing means for the housing.

95 The housing has an intake pipe extension comprising part 20 which is formed integrally with the body of the housing and a removable complementary section 20', the upper edge of which has a rib 21 corresponding to the ribs 18. The removable section of the housing and the main body 100 of the housing are provided with opposed ears 22 adapted to receive bolts whereby the removable section is effectively secured in place and at the same time may be removed 105 to permit the convenient assembling and 110

disassembling of the housing upon the engine.

The housing is provided with ports 23 and 24 at its ends provided with valves 25. 5 The valves are preferably connected by the link 26 so that they are simultaneously operated. The valve operating rod 27 is connected to the rear valve, the rod being disposed through the instrument board 28 for 10 convenience in manipulation. These valves are connected so that when one is opened the other is closed. As the carbureter pipe 29 is connected at one end of the housing there is a comparatively short path to the 15 pipe 29 for the air from the inlet valve at that end to the carbureter, and a long path from the other valve to the pipe 29, so that effective regulation of the heat is provided by manipulation of these valves. 20 I have not in the accompanying drawing attempted to maintain the relative proportions of the various parts as the same may be varied to meet various conditions which may exist in the adaptations. Further I 25 have not attempted to illustrate the various adaptations that are possible and contemplated by me as I believe the disclosure made will enable those skilled in the art to which my invention relates to embody or 30 adapt the same as may be desired.

Having thus described my invention, what I claim as new and desire to secure by Letters Patent is:

1. In an internal combustion engine, the 35 combination with the engine body, of a carbureter, intake and exhaust manifolds, manifold securing yokes and bolts, the bolts being extended through the yokes to engage a housing, a manifold housing comprising 40 front, end, top, and bottom walls embracing said manifolds, the top wall being lapped upon the top of the engine and provided with bolt openings through which the cap bolts of the engine are disposed, the front 45 wall being provided with bolt openings through which said manifold securing bolts are disposed, said housing being provided with a tubular intake pipe extension provided with a removable rear section, there 50 being opposed clamping ears on said removable section and adjacent parts of the housing whereby the removable section is secured in place, air inlets for said housing provided with valves connected for simultaneous operation, and an air intake pipe for said carbureter connected to said housing nearer one of said inlets than the other.

2. In an internal combustion engine, the 60 combination with the engine body, of a carbureter, intake and exhaust manifolds, manifold securing yokes and bolts, the bolts being extended through the yokes to engage a housing, a manifold housing comprising 65 front, end, top and bottom walls, embracing said manifolds, the top wall being lapped

upon the top of the engine and provided with bolt openings through which the cap bolts of the engine are disposed, the front wall being provided with bolt openings through which said manifold securing bolts 70 are disposed, air inlets for said housing provided with valves connected for simultaneous operation, and an air intake pipe for said carbureter connected to said housing nearer one of said inlets than the other. 75

3. In an internal combustion engine, the combination with the engine body, of a carbureter, intake and exhaust manifolds, manifold securing yokes and bolts, the bolts being extended through the yokes to engage a 80 housing, a manifold housing comprising front, end, top and bottom walls, embracing said manifolds, the top wall being lapped upon the top of the engine and provided with bolt openings through which the cap 85 bolts of the engine are disposed, the front wall being provided with bolt openings through which said manifold securing bolts are disposed, said housing being provided with a tubular intake pipe extension provided with a removable rear section, there being opposed clamping ears on said removable section and adjacent parts of the housing whereby the removable section is secured in place, and an air intake pipe for 90 said carbureter connected to said housing.

4. In an internal combustion engine, the combination with the engine body, of a carbureter, intake and exhaust manifolds, a manifold housing embracing said manifolds 100 and secured to said engine body, said housing being provided with a tubular intake pipe extension provided with a removable rear section, there being opposed clamping ears on said removable section and adjacent 105 parts of the housing, whereby the removable section is secured in place, and an intake pipe for said carbureter connected to said housing.

5. In an internal combustion engine the 110 combination with the engine body, of a carbureter, intake and exhaust manifolds, a manifold housing embracing said manifolds and secured to said engine body, said housing being provided with a tubular intake 115 pipe extension provided with a removable rear section, means for securing said removable section, and an intake pipe for said carbureter connected to said housing.

6. In an internal combustion engine the 120 combination with the engine body, of a carbureter, intake and exhaust manifolds, a manifold housing embracing said manifolds, air inlets for said housing provided with valves connected for simultaneous operation 125 so that one is opened as the other is closed, and an air intake pipe for said carbureter connected to said housing nearer one of said inlets than the other.

7. In an internal combustion engine the 130

combination with the engine body, of a carburetor, intake and exhaust manifolds, a manifold housing embracing said manifolds, air inlets for said housing provided with 5 valves, and an air intake pipe for said carburetor connected to said housing.

In witness whereof I have hereunto set my

hand and seal in the presence of two witnesses.
